UNITED STATES PATENT OFFICE.

LARKIN R. SHAFFER, OF GARLAND, UTAH.

SWITCH STAND.

Application filed June 16, 1926. Serial No. 116,423.

This invention relates to improvements in switch stands, one object of the invention being to improve upon the switch stand of the type shown and described in my prior

5 Patent No. 1,513,431, dated October 28, 1924.

In the locking arrangement shown in the patent the locking lever gradually becomes worn on account of its entering edge portion continually striking against the table

10 which is adapted to lock said lever against rotation. After said locking lever has become worn it is loose in the locking notch in said table and, as a consequence, neither said lever nor the switch point connected

15 thereto can be firmly locked. In the present case, however, the locking lever is so constructed as to prevent this wearing action thereon and, in addition, said lever is pro-

20 vided with a tapered or substantially knife edge portion which not only prevents wearing away of said lever but which also acts as a wedge to insure the table being turned to its proper locking position as well as to insure the switch point being returned to

25 its normal position.

Another feature of the present switch stand is that the casing which protects the lever locking mechanism is of sectional construction, thereby greatly facilitating the 30 assembly of the various parts within said casing.

With these and other objects in view the invention consists in certain novel details of constructions and combinations and arrangements of parts all as will hereinafter be more fully described and the novel features thereof particularly pointed out in the appended claims.

In the accompanying drawings,—

40 Figure 1 is a vertical sectional view of a switch stand embodying the present improvements;

Fig. 2 is a side elevation of the stand;

Fig. 3 is an edge view;

45 Figs. 4 and 5 are detail views of the locking lever;

Figs. 6 and 7 are elevational and sectional views, respectively, of the cap section of the casing; and

50 Fig. 8 is a sectional view of the base of said casing.

In the type of switch stand illustrated in the present instance the target shaft 10 has attached thereto, as by pins 11, the base section 12 of a casing which houses the locking mechanism of the switch operating lever 13,

said lever being pivoted in said casing as at 14 and adapted to normally assume a depending position with a portion thereof in a slot 15 of the table 16 as shown in dotted lines in Fig. 1. When the locking lever is in this depending position it is impossible to rotate the casing and the shaft to which the latter is affixed but by raising said lever and withdrawing it from said slot the casing, together with the target shaft 10, can be rotated to throw the switch.

With the construction such as shown in my prior patent continuous operation of the lever results in said lever being worn at that portion which enters the notch 15 due to the edge of said lever constantly abutting against the corner formed by the periphery of the table 16 and the wall of the slot 15.

After the lever has thus become worn it fails to make a close fit in the slot 15 and, as a consequence, the casing, together with the target shaft 10, is free to oscillate somewhat and move the switch point to a limited extent. In the present instance, this difficulty is overcome by having the lever 13 pivoted to one side of the table 16 and above said table so that the end portion of the lever will initially enter the slot 15 instead of the side edge first entering said slot.

In addition, this edge portion of the lever which initially enters said slot is tapered or formed with a knife-like edge, as indicated at 17, whereby it is not necessary that the entire lever register with the slot 15 in order to permit said lever to enter the slot. It is only necessary that the knife edge on the lever be positioned to enter said slot, in which event, the tapered portion of the lever will

act as a wedge against one wall of the slot and force or turn the casing to the position in which it should be locked, that is, a position which insures the switch point being properly closed or fully opened as the case may be. Furthermore, as shown in Fig. 1, this entering portion of the lever actually has nothing to do with the ultimate positioning of the casing, said tapered portion passing completely through the slot to a position above the table so that even if the

knife edge should be partially worn that portion of the lever immediately adjacent said tapered portion will not be worn and will make a close fit on the notch 15.

While various locking mechanisms may be employed for locking the lever in the table it is preferred that an arrangement

similar to that shown in my prior patent before referred to be employed. This locking arrangement comprises a pivoted member such as the crank 18 journaled in the casing 5 and loosely supporting a ring 19 which, when the lever is in its depending position, drops by gravity so as to position itself between said lever and a fixed abutment 20 within the casing section 12, thereby preventing the lever being raised until said crank 18 is elevated when being moved to the position shown in full lines in Fig. 1. It might here be stated that when the lever is in its depending position it may be locked 10 against unauthorized manipulation by a lock (not shown) placed in an eye 21 formed on the lever, as will be readily understood. This lock in the eye 21 prevents unauthorized use or operation of the switch while the locking mechanism composed of the ring 19 and crank 18 are for the purpose of holding the lever against accidental movement when the first mentioned lock has been removed from eye 21.

25 In order to facilitate assembly of the crank and ring in the casing said casing, in addition to the base section 12, has a detachable cap section 22, the said cap section being attached to the base section by a transverse bolt 23 partially located within the abutment 20. In the preferred construction the base and cap sections have overlapping edge portions, the upper edge of the base section and the lower edge of the cap section being 30 of reduced thickness so as to form an overlapping joint which will prevent the entry of water or snow or other matter which might interfere with the operation of the lock. To further facilitate assembly of the locking mechanism within the casing, bearings are provided in the overlapping edge portions of the casing cap and base with slots extending from said bearings to the edges of the respective members. For instance, in the base portion 12 of the casing there is a slot 24 extending from the upper edge to the bearing 25 in each side of the casing and in the cap there is a slot 26 extending from the side edge of said cap to 35 the bearing 27. With this arrangement the crank 18 is first inserted in the slot 26, the cap then placed on the base portion with the crank in registry with the entrances of slots 24; and said cap then moved downwardly and to one side to position the crank in the bearings 25, the upper edges of the base section 12 being cut away at one side, as at 28, to facilitate this application of the cap to the base section.

60 What I claim is:

1. In a switch stand, the combination of a casing, a table having a notch in the periphery thereof, and a pivoted switch operating lever adapted to normally occupy a position 65 within said notch when the stand is locked

and to be moved out of said notch when the switch is to be thrown, that portion of the lever initially entering said notch as the lever moves to locked position being tapered and said tapered portion being so located on the lever as to pass entirely through and without the notch when the lever fully assumes its locking position.

2. In a switch stand, the combination of a casing, a table having a notch in the periphery thereof, and a pivoted switch operating lever adapted to normally occupy a position within said notch when the stand is locked and to be moved out of said notch when the switch is to be thrown, that portion of the lever initially entering said notch as the lever moves to locked position being tapered and said tapered portion being so located on the lever as to pass entirely through and without the notch when the lever fully assumes its locking position, and the cross section of that portion of the lever ultimately resting within the notch being substantially equal to the width of said slot.

3. In a switch stand, the combination of a casing, a table having a notch in the periphery thereof, and a pivoted circular operating lever adapted to normally occupy a position within said notch when the stand is locked and to be moved out of said notch when the switch is to be thrown, said lever having a knife-like entering edge portion adapted to initially enter said slot when the lever is moved from its unlocked to its locking position.

4. In a switch stand, the combination of a casing, a table having a notch in its periphery and a switch operating lever adapted to normally occupy a position within said notch when the stand is locked and to be moved out of said notch when the switch is to be thrown, said lever being pivoted to one side of said table and above said table whereby that portion of the lever which initially enters said notch as the lever is moved to its locking position will pass entirely through and beyond said notch.

5. In a switch stand, the combination of a casing, a table having a notch in the periphery thereof, and a switch operating lever adapted to normally occupy a position within said notch when the stand is locked and to be moved out of said notch when the switch is to be thrown, said lever having a tapered portion adapted to initially enter said slot when the lever moves from its unlocked to its locking position, said tapered portion being adapted to lie at one side of the table when the lever is in its unlocked position and to lie above said table when the lever is in its locked position.

6. In a switch stand, a table, a target shaft, an operating lever connected to said shaft for rotating the latter, means for releasably locking said lever and table to-

gether to prevent rotation of the target shaft, a pivoted member for actuating said lever locking means, and a casing for said locking means, said casing comprising a base portion and a cap, and bearings in said casing cap and base for the pivoted operating member of the lever locking means and a cross pin extending through said base and cap for attaching said cap to the base.

10 7. In a switch stand, a table, a target shaft, an operating lever connected to said shaft for rotating the same, means for releasably locking said lever and table together to prevent rotation of said shaft, a pivoted member for actuating said lever locking means, a casing for said locking means, said casing comprising a base portion and a cap having overlapping edge portions at their top and bottom respectively, 15 and alined bearings in the overlapping edges of said casing cap and base for the pivoted operating member of the lever locking

means and a cross pin extending through said base and cap for attaching said cap to the base.

8. In a switch stand, a table, a target shaft, an operating lever connected to said target shaft for rotating the latter, means for releasably locking said lever and table together to prevent rotation of the target shaft, a pivoted member for actuating said lever locking means, a casing for said locking means comprising a base portion and a cap, and bearings in said casing cap and base for the pivoted operating member of the lever locking means, there being slots 30 extending from the bearings in the casing base to the upper edge of said base and there being slots extending from the bearings in the casing base to the upper edge of said base and there being slots extending from the bearings in the cap to the side edges of said cap.

LARKIN R. SHAFFER.
